UNITED STATES PATENT OFFICE.

HARRY R. BARTELL, OF ST. LOUIS, MISSOURI, ASSIGNOR TO COMMONWEALTH STEEL COMPANY, OF ST. LOUIS, MISSOURI, A CORPORATION OF NEW JERSEY.

BUFFER CASTING.

Application filed October 13, 1923. Serial No. 668,387.

My invention relates to railroad rolling stock and consists in an improved construction of that portion of a car underframe which is adjacent to the coupler.

5 In the preferred construction of my invention I form the striking plate, carry iron support, buffer stem housing, and forward draft lugs integrally, the object of which is to provide a construction of these parts 10 adapting them to be applied as a unit to the car underframe thereby eliminating the work and additional parts required for a built-up structure. Such construction will 15 occupy less space than the usual construction in which the parts mentioned are assembled with each other or separately secured to other parts of the car underframe by a far greater number of bolts and rivets. Greater clearances may be obtained and a 20 stronger structure provided and the weight and strength of the unit may be increased over the usual built-up construction as desired without requiring changes in the underframe members to which the casting is 25 applied.

A further object of my invention is to provide means for maintaining the distance between the center line of the coupler, supported indirectly by the buffer casting, and 30 the center line of the buffer stem, carried by the casting, without requiring the casting to be replaced.

35 My invention is especially adapted for passenger equipment and in the accompanying drawings I illustrate its application to the underframe of a passenger car.

In these drawings—

Figure 1 is a top view of my buffer casting with various associated parts shown 40 assembled therewith.

Figure 2 is a longitudinal vertical section through the same elements as shown in Figure 1.

45 Figure 3 is a front view of the same elements.

The buffer casting comprises side walls 1 and 2 adapted to engage the inner faces of the draft sills A of the car underframe and united at their tops by a horizontal web 3 which may be recessed at 4 to lighten the casting and to permit access to the buffer stem housing formed above the same. The forward end of walls 1 and web 3 terminate in a striking block 5 and supports 6 for a carry iron B, the block 5 being reinforced

by a flange 7 and web 8. The rear ends of walls 1 terminate in draft lug stops 9 braced by suitable webs 10. The side walls may be slotted at 11 to accommodate the key, not shown, of a draft yoke such as is in common use.

5 In the preferred construction of my invention I form the striking plate, carry iron support, buffer stem housing, and forward draft lugs integrally, the object of which is to provide a construction of these parts 10 adapting them to be applied as a unit to the car underframe thereby eliminating the work and additional parts required for a built-up structure. Such construction will 15 occupy less space than the usual construction in which the parts mentioned are assembled with each other or separately secured to other parts of the car underframe by a far greater number of bolts and rivets. Greater clearances may be obtained and a 20 stronger structure provided and the weight and strength of the unit may be increased over the usual built-up construction as desired without requiring changes in the underframe members to which the casting is 25 applied.

A further object of my invention is to provide means for maintaining the distance between the center line of the coupler, supported indirectly by the buffer casting, and the center line of the buffer stem, carried by the casting, without requiring the casting to be replaced.

My invention is especially adapted for passenger equipment and in the accompanying drawings I illustrate its application to the underframe of a passenger car.

In these drawings—

Figure 1 is a top view of my buffer casting with various associated parts shown assembled therewith.

Figure 2 is a longitudinal vertical section through the same elements as shown in Figure 1.

Figure 3 is a front view of the same elements.

The buffer casting comprises side walls 1 and 2 adapted to engage the inner faces of the draft sills A of the car underframe and united at their tops by a horizontal web 3 which may be recessed at 4 to lighten the casting and to permit access to the buffer stem housing formed above the same. The forward end of walls 1 and web 3 terminate in a striking block 5 and supports 6 for a carry iron B, the block 5 being reinforced

by a flange 7 and web 8. The rear ends of walls 1 terminate in draft lug stops 9 braced by suitable webs 10. The side walls may be slotted at 11 to accommodate the key, not shown, of a draft yoke such as is in common use.

5 In the preferred construction of my invention I form the striking plate, carry iron support, buffer stem housing, and forward draft lugs integrally, the object of which is to provide a construction of these parts 10 adapting them to be applied as a unit to the car underframe thereby eliminating the work and additional parts required for a built-up structure. Such construction will 15 occupy less space than the usual construction in which the parts mentioned are assembled with each other or separately secured to other parts of the car underframe by a far greater number of bolts and rivets. Greater clearances may be obtained and a 20 stronger structure provided and the weight and strength of the unit may be increased over the usual built-up construction as desired without requiring changes in the underframe members to which the casting is 25 applied.

A further object of my invention is to provide means for maintaining the distance between the center line of the coupler, supported indirectly by the buffer casting, and the center line of the buffer stem, carried by the casting, without requiring the casting to be replaced.

My invention is especially adapted for passenger equipment and in the accompanying drawings I illustrate its application to the underframe of a passenger car.

In these drawings—

Figure 1 is a top view of my buffer casting with various associated parts shown assembled therewith.

Figure 2 is a longitudinal vertical section through the same elements as shown in Figure 1.

Figure 3 is a front view of the same elements.

The buffer casting comprises side walls 1 and 2 adapted to engage the inner faces of the draft sills A of the car underframe and united at their tops by a horizontal web 3 which may be recessed at 4 to lighten the casting and to permit access to the buffer stem housing formed above the same. The forward end of walls 1 and web 3 terminate in a striking block 5 and supports 6 for a carry iron B, the block 5 being reinforced

pler to be maintained at the required distance from the rail and from the center line of the buffing stems.

This latter distance may be kept constant 3 also by changing the wear plates D for thicker or thinner plates as may be required. During normal operation of the car both the carry iron and wear plates will be subject to wear due to the friction of the 10 coupler shank and buffer stems respectively and the above described construction makes it easy to take care of this wear without removal of or other work on the buffer casting as a whole.

15 Various modifications in the details of my construction may be made without departing from the spirit of my invention as expressed in the appended claims.

I claim:

20 1. A railway car member comprising a buffer stem and spring housing, a coupler striking plate, carry iron supports, and a pair of transversely spaced front draft lugs, all formed integrally and applicable as a 25 unit to the car draft sills.

2. A railway car member comprising a buffer stem and spring housing, a coupler striking plate, carry-iron support elements, and a pair of front draft lugs all formed 30 integrally and terminating at the sides of said housing and applicable as a unit to the draft and end sills of a car.

3. A railway car underframe member adapted to be applied to or removed from 35 car draft sills as a unit and comprising spaced vertical walls adapted to be secured to the car draft sills and having forward draft lugs integrally formed on the rear portions of said walls, a striking plate and 40 coupler carry iron supports integrally formed on the front portion of said walls, and an integrally formed upward extension forming a buffer plate and buffer stem housing extending above and forwardly from 45 the draft sills.

4. In a railway car device, a casting comprising a striking plate, a box-shaped portion above said plate for housing a buffer stem and spring, rearward projections beneath said housing portion for attaching 50 the device to car draft sills and terminating in draft lugs, vertical webs connecting said housing portion and said projections adjacent to said lugs, and vertical webs connecting said striking plate and said housing portion.

5. In a railway car, draft sills, a buffer casting including a buffer stem housing, the rear lower portion of which extends over and is secured to the top of said draft sills, 60 integral walls extending downwardly from said portion inside of and secured to sides of said draft sills, and integral inward projections on said downwardly extending walls forming complete draft lugs. 65

6. In a railway car device, a casting comprising a box-shaped upper portion forming a housing for buffer stems and springs and adapted to overlie the draft sills of a car, a rearwardly extending horizontal 70 flange on said housing similarly adapted, walls depending from said housing and flange and terminating at opposite ends in a coupler striking plate and front draft lug, respectively, and webs bracing said flange 75 and plate from said housing.

7. In a railway car casting, a buffer housing having a rear wall forming a buffer spring seat, vertical flanges depending from 80 said housing and terminating in front draft lugs spaced below and rearwardly of said wall, a horizontal flange connecting said vertical flanges and extending rearwardly of said wall, and vertical webs extending diagonally downward from said wall to the 85 rear of said horizontal flange.

In testimony whereof I hereunto affix my signature this 2nd day of October, 1923.

H. R. BARTELL.
